Attorney:

UNITED STATES PATENT OFFICE.

GEORGE T. PHILLIPS, OF VOLUNTOWN, CONNECTICUT.

CARTRIDGE-CRIMPER.

No. 876,584.

Specification of Letters Patent.

Patented Jan. 14, 1908.

Application filed July 22, 1907. Serial No. 384,901.

To all whom it may concern:

Be it known that GEORGE T. PHILLIPS, a citizen of the United States, residing at Voluntown, in the county of New London and 5 State of Connecticut, has invented certain new and useful Improvements in Cartridge-Crimpers, of which the following is a specification.

This invention relates to cartridge crimpers and is designed to form an internal annular crimp or bead in a paper shell for the purpose of holding the wad in place. By producing an annular crimp or bead, in contradistinction to folding inwardly the end of the 15 shell, the shell may be repeatedly used, as the damage by repeated crimpings is very slight.

A further object of the invention is to have the parts thereof assembled in compact relation and to enable the convenient manipulation thereof to quickly and successfully crimp a cartridge without requiring any particular degree of skill or experience.

With these and other objects in view, the present invention consists in the combination 25 and arrangement of parts as will be herein-after more fully described, shown in the accompanying drawings and particularly pointed out in the appended claims, it being understood that changes in the form, proportion, size and minor details may be made 30 within the scope of the claims without departing from the spirit or sacrificing any of the advantages of this invention.

In the drawings, Figure 1 is a side elevation 35 of a cartridge crimper embodying the features of the present invention. Fig. 2 is a top plan view thereof. Fig. 3 is a front elevation. Fig. 4 is a longitudinal sectional view. Fig. 5 is a detail cross sectional view 40 taken through the crimping elements. Fig. 6 is a side elevation of a cartridge crimped by the present device.

Like characters of reference indicate corresponding parts in each of the several figures 45 of the drawings.

For the support of the working parts of the present invention, there is provided a substantially U-shaped crimping or supporting frame 1, the lower arm of which is pierced by 50 a clamping screw 2 provided at its lower end with a finger piece and at its upper end with a swiveled head 3, whereby the frame may be clamped upon the edge of the table or other support.

Rising from the rear end of the frame there

is a tubular bearing 4, and upon the top of the bearing is a pair of spaced perforated ears 5.

The working parts of the crimping mechanism comprise a bifurcated tube 6 provided at its rear end with a reduced cylindrical journal 7 mounted to rotate in the bar 4 and provided at its rear end with a concentric stud or projection 8 carrying a crank handle 9. By preference this crank handle is removable and may have a screw-threaded connection with the stud as illustrated in the longitudinal sectional view of the drawings. Located concentrically within the tube 6 is a cylindrical center element 10, preferably tubular, and having its forward end reduced to provide a cylindrical flange 11. Loosely embracing the center element are a pair of crimping jaws 12, each of which is substantially semi-circular in shape and provided upon its inner side with 75 a substantially semi-cylindrical flange 13 designed to embrace the reduced or flanged portion 11 of the center element. Extending rearwardly from each jaw is a shank 14, and the two shanks are pivotally connected 80 at their rear ends by means of a pivot pin 15 passing through spaced ears 16 on the shanks. The rear end of the center element is provided with a perforate ear 17 received between the ears 16 and pierced by the pivot 85 pin. It will here be noted that the shanks 14 work in the slotted or bifurcated portion of the tube 6, and the pivot pin 15 passes through alined perforations 18 in opposite sides of the tube. A suitable spring 19 acts 90 upon the shanks of the jaws with a tendency to force the same outward.

The tube 6 is rotatably received within a sleeve 20 provided with a pair of diametrically-opposite forwardly-projecting fingers 95 21 frictionally engaging the respective shanks of the jaws. One end of the pivot pin 15 projects externally of the tube and engages a longitudinal open-ended guideway or slot 22 in the inner wall of the sleeve, whereby 100 the sleeve and the tube rotate together, and the latter is permitted to move endwise independently of the tube, whereby the fingers 21 working over the shanks of the jaws force the latter together when the sleeve moves 105 outwardly, the jaws being spread apart by the influence of the spring when the sleeve is fed backward.

Supported upon the front part of the top of the frame 1 is a suitable clamp for hold-

ing the cartridge or shell during the crimping operation. This clamp comprises a pair of jaws 23 and 24 respectively provided with the handles 25 and 26 normally forced 5 apart by a spring 27.

Pivoted between the spaced ears 5 is a lever 28 having a depending detent or projection 29 received within a spiral guideway 30 on the sleeve, the free end of the lever 10 playing in a socket or guideway 31 in the rear side of the upper handle 25.

In practice, the paper shell or cartridge, such as shown at 32 in Fig. 4 of the drawings, is slid endwise through the cartridge 15 holding clamp with its open end received within the clamping mechanism between the center 10 and the crimping jaws 12. When the handles of the cartridge-engaging clamp are pressed together so as to clamp the jaws 20 snugly upon the cartridge and hold the same, the lever 28 is depressed until its detent or projection 29 engages the spiral guideway 30, and when the crank handle is operated the tube 6 will be rotated and the sleeve fed 25 forwardly. As the sleeve feeds forwardly, the crimping jaws are gradually pressed against the shell and the latter is crimped by the jaw flanges 13 around the cylindrical flange 11 of the center 10. When the handles of the cartridge-holding clamp are released and swung apart, the lever 28 will be lifted with the handle 25, thereby freeing the sleeve 20 to longitudinal movement, whereupon the crimping jaws will spring 35 outward under the influence of the spring so as to release them from the cartridge and permit of the latter being withdrawn from the device with an internal annular crimp or bead pressed therein.

40 What is claimed is:—

1. A cartridge crimper comprising a cartridge-holding clamp, rotatable mechanism for engaging and crimping a cartridge held in the clamp, and means controlled by the 45 clamp for controlling the crimping action.

2. A cartridge crimper having a cartridge holding clamp, a rotatable and radially movable crimping jaw, a feed sleeve embracing and rotatable with the jaw and capable of 50 endwise movement thereon to force the same inwardly, the sleeve being provided with a spiral guideway, and means controlled by the

clamp for engagement with the spiral guideway to move the sleeve endwise under the rotary movement thereof.

55

3. A cartridge crimper having a rotatable and radially movable crimping jaw, a feed sleeve embracing and rotatable with the jaw and capable of endwise movement thereon to force the same inwardly, and means arranged 60 to feed the sleeve endwise under the influence of the rotary movement thereof.

4. A cartridge crimper comprising a bifurcated rotatable tube, a pair of rotatable radially movable crimping jaws having pivotally-connected shanks working in the bifurcated portions of the tube, a spring normally tending to separate the jaws, a center element embraced by the jaws, a pivot pin common to the center and the shanks of the 70 jaws and piercing the tube one end of the pin projecting externally of the tube, a feed sleeve embracing the tube and having a longitudinal guideway receiving the projecting end of the pin, said sleeve having portions 75 coöperating with the jaws to force the latter inwardly when the sleeve is slid forward, and means to feed the sleeve endwise when the tube is rotated.

5. A cartridge crimper having a cartridge 80 holding clamp, a center element, a rotatable and radially movable crimping jaw coöperating with the center element, a feed sleeve embracing and rotatable with the jaw and capable of endwise movement thereon to force the same inwardly, and means arranged 85 to feed the sleeve endwise under the influence of the rotary movement thereof.

6. A cartridge crimper having a center element, a pair of rotatable and radially movable crimping jaws embracing and coöperating 90 with the center element, a feed sleeve embracing and rotatable with the jaws and capable of endwise movement thereon to force the same inwardly towards the center element, and means arranged 95 to feed the sleeve endwise under the influence of the rotary movement thereof.

In testimony whereof I affix my signature, in presence of two witnesses.

GEORGE T. PHILLIPS.
